UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

SIX-WHEEL CAR-TRUCK.

1,371,587.

Specification of Letters Patent. Patented Mar. 15, 1921.

Application filed March 15, 1920. Serial No. 365,823.

To all whom it may concern:

Be it known that I, CHARLES T. WESTLAKE, a citizen of the United States, residing at St. Louis, Missouri, have invented a 5 certain new and useful Improvement in Six-Wheel Car-Trucks, of which the following is a full, clear, and exact description, such as will enable others skilled in the art to which it appertains to make and use the 10 same, reference being had to the accompanying drawings, forming part of this specification.

My invention relates generally to railway car truck construction and more particularly to an improved arrangement whereby 15 the weight of loads imposed on the main truck bolster are transmitted to and evenly distributed between the journals of the three axles associated with the truck.

20 The principal objects of my invention are, to generally improve upon and simplify the construction of the existing types of six wheel trucks; to materially increase the flexibility of the truck; to provide for the 25 equal distribution and absorption of shocks and vibration due to track irregularities and prevent such shocks and vibrations from being transmitted to the car body; and, further, to provide a strong durable truck which, by 30 virtue of its relatively simple construction and few parts, may be easily and cheaply produced.

My invention consists of a main bolster having cross members on its ends, said cross 35 members being disposed centrally between the middle and outer axles, the projecting ends of said cross members resting upon springs of unequal strength and said springs being supported by side frame members 40 which in turn are supported by the truck journal boxes. By properly proportioning the strength or tension of the springs, two-thirds of the supported load will be transmitted to the outer axles, and one-third to 45 the inner axle, thus equally distributing said load between all of the journals.

With the foregoing and other objects in view, my invention consists in certain novel features of construction and arrangement 50 of parts, hereinafter more fully described and claimed, and illustrated in the accompanying drawings, in which—

Figure 1 is a plan view of a six wheel truck of my improved construction, parts 55 thereof being broken away.

Fig. 2 is a side elevational view of the truck.

Fig. 3 is a cross section taken approximately on the line 3—3 of Fig. 2.

Referring by numerals to the accompanying drawings, which illustrate a practical embodiment of my invention, 10, 10 designate ordinary wheel carrying axles, the journals of which are positioned in ordinary journal boxes 11. Supported by the 15 middle journal box are the inner ends of a pair of side frame members 12, the outer ends thereof being supported by the journal boxes for the outer pair of axles. These side frame members are arranged upon the journal boxes in any desired and convenient manner, which will permit them to move 20 vertically independent of each other, and as illustrated in Fig. 1, I prefer to bifurcate the inner end of one of said members 25 as designated by 12 and arrange the inner end 14 of the other member between the legs or parts formed by such bifurcation. The parts of the side frame members intermediate the end portions which rest upon the 30 journal boxes are depressed so that their upper surfaces occupy a plane substantially below the plane occupied by the ends of said members.

The truck bolster which is preferably 35 formed in a single piece by casting, includes a pair of transversely arranged spaced center members 15, a pair of side bearing members 16, and a pair of transversely disposed end members 17. The central portions of 40 the center members 15 are united by a horizontally disposed web or plate 18 and arranged thereupon is a center bearing 19. The side bearing members 15 occupy positions inside and adjacent to the wheels on 45 the central one of the axles 10 and the cross members 17 are positioned at points substantially halfway between the center axle and the end axles. These cross members 17 are 50 extended laterally beyond the ends of the side bearing members 16 and formed integral with their outer ends are short rail members 20 which, when the parts of the truck are properly assembled, occupy 55 positions immediately above the depressed intermediate portions of the side frame members 12.

The ends of the members 20 have sliding connection with upright portions 12^a of the side frame members between the depressed 60

central portions and the end portions which bear upon the journal boxes, and the parts are interlocked against lateral movement and guided during their vertical sliding movement by vertically disposed ears or lips 5 21 that are formed on the ends of the members 20 and overlie the sides of the upright portions 12^a of the side frame members.

Interposed between the ends of the members 20 that are adjacent to the middle journal box and the inner portions of the side frame members 12 are springs 22 and interposed between the opposite or outer ends of said members 20 and the portions of the 15 side frames which are adjacent to the outer journal boxes 11 are springs 23. These springs are arranged in multiple, *i. e.* side by side as contra-distinguished from a tandem arrangement, that is, end to end; therefore, springs 22 and 23 carry all of the load 20 imparted to them directly and without transmitting it through another spring, as in the tandem arrangement mentioned. The springs 23 are relatively heavier and therefore have greater load carrying capacity 25 than the springs 22, the proportions being such that two-thirds of the weight of the loads imposed by the truck frame on the two sets of springs will be transmitted to the outer axles and one-third to the middle axle. As a result of this arrangement, the 30 weight of loads carried by the truck frame is distributed equally between the three journals on each side of the truck and consequently distributed equally between all of 35 the truck journals.

While I prefer to form the entire bolster and the side frame members in single pieces by casting, it will be understood that said 40 parts may be of assembled or fabricated structure. Where the bolster is cast in a single piece, the parts 15, 16 and 17 are preferably channel-shape with horizontally disposed flanges and the members 20 are preferably of inverted U-shape, this latter formation providing housings for the upper 45 portions of the springs 22 and 23.

The load distributing arrangement contemplated by my invention is comparatively 50 simple, may be easily and cheaply manufactured, materially increases the flexibility of the truck, and is very effective in performing its intended functions.

It will be readily understood that minor 55 changes in the size, form and construction of the various parts of my improved six-wheel car truck may be made and substituted for those herein shown and described, without departing from the spirit of my 60 invention, the scope of which is set forth in the appended claims.

I claim:

1. A flexible support for railway car trucks comprising side frame members supported by the journal boxes associated with

the truck, a pair of springs arranged in multiple and bearing upon each side frame member, said springs having different load carrying capacities, and a truck bolster supported by said springs. 70

2. A flexible support for railway car trucks comprising a pair of separately formed side frame members supported by the journal boxes associated with the truck, a pair of springs arranged in multiple and supported by each side frame member, one of said springs having greater carrying capacity than the other, and a truck bolster supported by said springs. 75

3. A flexible support for railway car trucks comprising a pair of separately formed side frame members supported upon the journal boxes associated with the truck, a truck bolster having parts overlying the intermediate portions of said side frame 80 members, and a pair of springs arranged in multiple and having different load carrying capacities disposed between each side frame member and the bolster part overlying the 85 same. 90

4. In a six wheel car truck, a pair of co-operating separately formed side frame members supported by the journal boxes of the truck, relatively light springs supported by said side frame members adjacent to the 95 middle journal box, heavier springs supported by said side frame members adjacent to the outer journal boxes, and a truck frame supported by said springs. 95

5. In a six wheel car truck, a pair of separately formed side frame members supported by the truck journal boxes, a truck bolster having parts overlying the intermediate portions of each of said side frame members and operating in open ended recesses or pockets therein, and springs in said open ended pockets and interposed between said side frame members and the overlying parts of the bolster, which springs are arranged so as to equally distribute between 105 the truck journals the weight of loads imposed on the truck frame. 105

6. In a six wheel car truck, a pair of separately formed side frame members supported by the truck journal boxes, a truck bolster 110 having parts overlying the intermediate portions of said side frame members, and a pair of springs arranged in multiple and interposed between each side frame member and the overlying portion of the truck 115 bolster, the members of each pair of springs having different load carrying capacities. 120

7. In a six wheel car truck, a pair of separately formed side frame members supported by the truck journal boxes, a truck bolster 125 having parts overlying the intermediate portions of said side frame members, and a pair of springs interposed between each side frame member and the overlying portion of the truck bolster, the members 130

of each pair of springs having different load carrying capacities, and disposed so as to equally distribute between the truck journals the weight of loads imposed on the 5 truck bolster.

8. In a six wheel car truck, a pair of separately formed side frame members, the inner ends of which bear upon the middle journal box of the truck, the outer ends of 10 said members bearing upon the outer jour-

nal boxes, a pair of springs supported by each side frame member, said springs having different load carrying capacities and with the heavier spring positioned adjacent to the outer journal box, and a bolster supported 15 by said springs.

In testimony whereof I hereunto affix my signature this 9th day of March, 1920.

CHARLES T. WESTLAKE.
